United States Patent Office

Des. 200,639
Patented Mar. 23, 1965

200,639

CHAIR

Robert E. Kjer Jakobsen, Manhattan Beach, Calif., assignor to Schlumberger Limited, Houston, Tex., a corporation of the Netherlands Antilles

Filed Mar. 31, 1964, Ser. No. 79,265

Term of patent 14 years

(Cl. D15—1)

FIG. 1 is a front perspective view of a chair showing my design; and

FIG. 2 is a rear perspective view thereof.

I claim:

The ornamental design for a chair, substantially as shown.
